UNITED STATES PATENT OFFICE.

JOSEPH E. MOODY, OF STAMFORD, TEXAS.

CULTIVATOR ATTACHMENT.

1,074,729.

Specification of Letters Patent.

Patented Oct. 7, 1913.

Application filed February 8, 1913. Serial No. 747,195.

To all whom it may concern:

Be it known that I, JOSEPH E. MOODY, a citizen of the United States, residing at Stamford, in the county of Jones and State 5 of Texas, have invented a new and useful Cultivator Attachment, of which the following is a specification.

The present invention appertains generally to earth tilling implements and relates 10 particularly to an attachment for riding, wheel mounted or sulky cultivators.

One of the objects of the present invention is to provide an attachment of the character indicated embodying a center piece attachable to the foot or other suitable part of a cultivator in connection with a pair of beams for carrying the earth tilling elements, and which beams are pivotally and adjustably connected to the center piece in 20 order that they may be set or adjusted according to the circumstances.

Another object of the present invention is to provide novel means for clamping or securing reversible soil tilling elements to the 25 respective beams, in order that the tilling elements may be reversed and in order that they may be held in vertical or inclined positions.

With the foregoing general objects and 30 other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

40 The invention has been illustrated in its preferred embodiment in the accompanying drawings, wherein similar reference characters have been employed to denote corresponding parts, and wherein:

45 Figure 1 is a perspective view of the attachment. Fig. 2 is a fragmental detail thereof showing attachment secured to the foot or depending portion of a cultivator.

Referring specifically to the drawings, the 50 present invention embodies a pair of angle iron beams or "wings" 3 having their forward ends flattened and inturned as designated by the numeral 4. These beams are

attached to a longitudinal center piece 5, which is preferably fashioned from a bar of 55 metal and which has its forward ends bent back and turned upward to provide a standard 6, the bend being formed into an eye 7. Through the eye 7 there is passed an upright member or shank 8, and the forward 60 ends of the beams are pivoted to the shank 8 so as to overlap or overlie the eye 7. A pair of nuts 9 are threaded upon the shank 8 in order to clamp the eye 7 and the forward ends of the beams together, the lower end of 65 the member or shank 8 being preferably formed or fashioned into a plow point 10. An open link 11 is engaged over the center piece or bar 5 below the standard 6 and stands loosely around the shank 8 below the 70 forward ends of the beams.

The standard 6 is provided with a plurality of bolt holes through which bolts or other securing members may be passed to secure or clamp the standard to the foot or 75 other depending part of a cultivator, as depicted in Fig. 2. The link 11 is adapted to loosely embrace the cultivator foot in order that the attachment may trail loosely in rear of the foot, so that it will be seen that 80 the attachment may be secured either rigidly or loosely to the foot of the cultivator according to the requirements which herein-after more fully appear.

The rear or free ends of the beams are 85 adjustably connected to the center piece by means of the respective braces or arms 12 having their outer ends pivoted to the horizontal flanges of the beams by means of bolts or other pivot members and having their 90 inner ends provided with the slots 13, a bolt or other clamping member 14 being carried by the rear end of the center piece or bar 5 and working through the slots 13. Thus, when the bolt 14 is loosened, the beams may 95 be adjusted relative to each other and relative to the center piece, and when the bolt 14 is tightened, the beams will be held in fixed position.

Each of the beams is provided with a 100 series of openings or apertures 15 in its horizontal flange, the horizontal flanges, projecting inwardly or toward each other, and a narrow tooth or earth tilling element 16 being passed through each of the openings 15 105 so as to rest or bear against the inner face or

side of the respective upright flange. One end of each earth tilling element 16 is pointed so as to provide a harrow tooth, and the other end is fashioned or formed into a diamond shaped or other plow point 17, it being noted that either end of the earth tilling element may be disposed lowermost or in active position to engage the soil.

In order to clamp the harrow teeth or earth tilling elements in position, bolts 18 have been passed loosely through the upright flanges of the beams, one bolt being disposed above each opening 15. These bolts 18 are provided with the nuts 19 on their outer ends resting or seating against the outer faces or sides of the upright flanges of the beams, and the inner ends of the bolts are bent into hooks in order to embrace the harrow teeth or earth tilling elements. The bolts 18 are preferably and approximately disposed directly above the forward ends of the respective slots 15, while an aperture or opening 20 is provided in each upright flange directly above the other or rear end of each opening, a second opening 21 being provided adjoining each bolt 18. This opening 21 is disposed in advance of the respective bolt 18, but in a slightly lower plane. The inner hooked ends of the bolts 30 may be swung to either side, or rearwardly and forwardly to engage the harrow teeth or earth tilling elements when they are either in a vertical or inclined position.

To each of the beams 3, there has been attached a fender or guard 22, preferably bent from a rod passing or extending along or slightly above the upper or inactive ends of the harrow teeth or earth tilling elements and having its ends bent downwardly and riveted or otherwise secured to the upright flange of the respective beam.

In use, it will be evident from the foregoing, that the standard 6 may be bolted or otherwise secured to the foot or other depending part of the cultivator in order that the beams may be raised and lowered or actuated with the foot of the cultivator to positively bring the earth tilling elements into and out of engagement with the soil. It will also be obvious that the attachment 50 may be loosely connected to the foot or other suitable depending part of the cultivator by means of the link 11 so that the attachment may drag or trail in rear of the foot. When the present attachment is employed as a harrow, the link 11 is preferably connected to the foot of the cultivator, whereas when the attachment is employed as a cultivator plow, the standard 6 is 60 preferably secured to the foot of the cultivator so that the plow points may be swung positively into and out of engagement with the soil. Each or both of the beams may be adjusted relative to the center piece so that 65 the beams will be most effectively positioned

to accomplish the result desired, it being noted that the pivotal member for the beams also serves as an earth tilling element.

The present attachment may be employed either as a harrow or as a cultivator plow, 70 as above indicated, which results are accomplished by properly setting or adjusting the earth tilling elements. When the device is to be employed as a harrow, the harrow teeth 16 are passed through the 75 openings 15 so that their pointed ends are lowermost, and the bolts 18 are then tightened in order to hold the harrow teeth in position. The harrow teeth may be set in an inclined position so that they may drag 80 over the soil in an effective manner, in which event, the bolts 18 are swung so that the hooks project forwardly and embrace the harrow teeth. When the device is to be employed as a cultivator plow, the plow 85 points 17 are disposed lowermost or in position to engage the soil, the earth tilling elements or harrow teeth being held in an upright or vertical position by swinging the hooks of the bolts 18 rearwardly. As illustrated in Fig. 1, the earth tilling elements of one beam are set to serve as a cultivating plow, and the elements of the other beam are set to serve as a drag harrow.

The means for clamping the harrow teeth 95 or earth tilling elements in position is an effective and simple one, and not only permits the reversal and adjustment of the harrow teeth, but also serves to hold the same substantially in position. It will be noted that the free ends of the bolts 18 are adapted to engage in either of the openings 20 or the openings 21 according to the position of the harrow teeth.

The fenders or guards 22 protect the upper or inactive ends of the harrow teeth or earth tilling elements and prevent the entanglement of the stalks or plants with the upper or inactive ends of the harrow teeth, and also prevent the upper ends of the teeth 110 from breaking or pulling off the limbs or bolls of cotton plants.

It is to be understood, that any number of the attachments may be employed in a single cultivator, according to the nature of the 115 cultivator, in order that one or more rows of the plants may be worked at the same time. The beams of each attachment may be adjusted relative to each other and relative to the center piece in order to adapt 120 the attachment to various widths of rows, the adjustment being a simple one.

The attachment may also be applied to the cultivator foot in such a manner that the harrow teeth will follow or trail after the 125 cultivator plow, so as to level the soil and close the furrow made by the cultivator plow, which will serve to preserve the moisture. The plow points permit of shallow plowing and also assist in destroying for- 13

sign vegetation and at the same time leave the land smooth and in such a condition as not to permit the air to penetrate the surface readily, which would permit the moisture to 5 readily evaporate.

The present attachment is also light and comparatively simple and of such a construction as to provide for strength and durability. It is also possible to adjust the 10 harrow teeth or earth tilling elements so that they will project into the soil at various depths according to the requirements.

What is claimed is:

1. A cultivator attachment embodying a 15 center bar having its forward end bent back and turned upward to provide a standard attachable to the foot of the cultivator, a pair of beams pivoted to the forward end of the center bar, earth tilling elements carried by the beams, and heel braces adjustably connecting the beams and the rear end of the center bar.

2. A cultivator attachment embodying a 25 center bar having its forward end bent back and turned upward to provide a standard attachable to the foot of a cultivator, a pair of angle iron beams having their forward ends flattened and pivoted to the forward end of the said bar, earth tilling elements 30 carried by the beams, and heel braces adjustably connecting the beams and the rear end of the said bar.

3. A cultivator attachment embodying a 35 center bar having its forward end bent back and turned upward to provide a standard and having an eye formed at the bend, a pivot member passing through the eye, a pair of beams pivoted to the said pivot member, members adjustable on the pivot

member to clamp the beams and the eye together, earth tilling elements carried by the beams, and brace members adjustably connecting the beams and center bar. 40

4. A cultivator attachment embodying a 45 center bar having its forward end bent back and turned upward to provide a standard and having an eye formed at the bend, an earth tilling element having a shank passing through the eye, a pair of angle iron beams having their forward ends flattened 50 and pivoted to the said shank, nuts threaded on the shank to clamp the eye and ends of the beams together, earth tilling elements carried by the beam, and brace members adjustably connecting the free ends of the 55 beams and the rear end of the center bar.

5. A cultivator attachment embodying a 60 center bar having an upturned standard at its forward end, a pivot member carried by the center bar in advance of the standard, a pair of beams pivoted to the pivot member, earth tilling elements carried by the beams, and heel braces adjustably connecting the beams and center bar.

6. A cultivator attachment embodying a 65 center bar having its forward end bent back and upturned to provide a standard, beams pivoted to the center bar in advance of the standard, and means for adjustably connecting the beams and center bar. 70

In testimony that I claim the foregoing as my own, I have hereto affixed my signature in the presence of two witnesses.

JOSEPH E. MOODY.
